UNITED STATES PATENT OFFICE

HARRISON ELIGHUE LANE, OF FAIRVIEW, OKLAHOMA.

COIN-CONTROLLED LOCK.

948,894.

Specification of Letters Patent.

Patented Feb. 8, 1910.

Application filed February 16, 1909. Serial No. 478,186.

To all whom it may concern:

Be it known that I, HARRISON E. LANE, a citizen of the United States of America, residing at Fairview, in the county of Woods and State of Oklahoma, have invented new and useful Improvements in Coin-Controlled Locks, of which the following is a specification.

This invention relates to coin controlled locks, and one of the principal objects of the same is to provide a simple, reliable and efficient lock to be used on small compartments in public places, said compartments designed to receive small articles like umbrellas, hand satchels, traveling bags, etc., and which will be rendered operable by a coin dropped into a slot in the lock casing.

Another object of the invention is to provide simple and reliable means to secure small articles in a compartment or closet and to render the articles accessible only to the person who has obtained the key of the lock and deposited a coin in the lock casing.

These and other objects may be attained by means of the construction illustrated in the accompanying drawings, in which—

Figure 1 is a face view looking at the inside of a lock made in accordance with my invention, said lock being shown in unlocked position with a coin in place for rendering the lock operative for locking the door to which said lock is attached. Fig. 2 is a similar view, showing the bolt in locked position, a portion of the device being broken away to better illustrate the parts. Fig. 3 is a view in elevation, showing the lock casing and coin receptacle and slot in section. Fig. 4 is a vertical section on the line 4—4 of Fig. 3. Fig. 5 is a similar view on the line 5—5 of Fig. 3. Fig. 6 is a longitudinal section of the casing and showing the operative parts of the lock in plan. Fig. 7 is a detail perspective view, showing the parts of the lock disconnected.

Referring to the drawings, the numeral 1 designates a door, and 2 is the door frame. Secured to the door is a lock made in accordance with my invention, said lock comprising a casing 3 preferably made in sections and provided with a coin tube or mouth 4 and a coin box or receptacle 5. Mounted to slide in the casing 3 is a bolt 6 provided with an enlarged outer end 7 and a coin recess 8 adjoining the head 7. A rib 9 separates the coin recess from the inner portion of the bolt. The inner portion 10 of

the bolt is of equal thickness from end to end and is provided with a stud 11 and slots 12. The tumbler 13 of the lock is provided with an angular flange 14 which is disposed in the coin recess 8 of the bolt. Slots 12^a in the tumbler 13 are arranged coincidently to the slots 12 in the bolt, and pins 15 which are utilized for securing the two members of the casing together extend through the slots 6, 12 and 12^a to hold the bolt and tumbler in relative position. The pin 11 spans the space between the inner walls of the bolt and the tumbler. Formed in the lower edge of the tumbler is a key recess 16, the diverging walls 17 and 17^a of said recess extending to the lower edge of said tumbler. Pivoted upon one of the pins 15 is a gravity latch 18, said latch having a recess 19 in its outer end and a stop shoulder 20 back of said recess.

A coin-supporting element 21 is pivoted upon a pin 22 connected to opposite sides of the casing, said coin-supporting element being disposed immediately under the sliding bolt and serving to support the coin in the recess 8 of the bolt during the operation of the lock. Projecting from the inner end of the coin-supporting element 21 is a finger 23 which is of reduced width compared to the element 21, said finger occupying the space 85 between the tumbler 13 and the portion 10 of the bolt when the bolt has been moved to its locking position, thus permitting the coin-supporting element to drop to the position shown in Fig. 2. A keyhole 24 is 90 formed in the casing, and a key 25 is adapted to operate the bolt.

My lock may be operated in the following manner: A person desiring to have access to a room or compartment provided with a lock made in accordance with my invention may obtain a key, like 25, and this key inserted in the lock casing will not operate the bolt until a coin or check is inserted in the coin chute 4, for the reason that the flange 14 of the tumbler will move freely in the recess in the bolt but will not operate the bolt. When a coin *a* is inserted in the coin chute 4, the key 25 moving against the wall 17 of the keyhole recess 16 will carry the bolt forward to engage the keeper in the door frame 2. When the bolt is in locked position the gravity latch 18 drops to engage the stop pin 11, as shown in Fig. 2. The coin-supporting element 21 is dropped 110 to the position shown in Fig. 2, and the finger 23 occupies a position between the

wall 10 and the inner wall of the tumbler 13. When the key 25 is again inserted in the lock for the purpose of moving the bolt backward into the lock casing, the latch 18 is first 5 raised by the key, and then the tumbler 13 is moved backward within the casing, drawing with it the bolt and at the same time bringing the coin-supporting element 21 back into horizontal position to cover the 10 bottom of the coin recess 8. In this position the key will not again operate the bolt without the insertion of a coin in the recess 8.

From the foregoing, it will be obvious that a lock made in accordance with my invention is of comparatively simple construction, can be manufactured at slight cost, is composed of very few parts, cannot be operated without the use of a coin and is very desirable and efficient for its purpose.

20 I claim:—

1. A coin-controlled lock comprising a casing having a coin chute and a coin receiver, a bolt mounted in said casing, said bolt provided with a coin recess, a coin-supporting lever pivoted below said recess and 25

provided with an extension beyond its pivotal point, a tumbler mounted at the side of said bolts provided with a recess for a key, a rib extending across said bolt, a flange formed on said tumbler to space said tumbler and bolt apart and to permit the extended portion of the coin support to lie between said members, and a pivoted latch and stop for holding the bolt in projected position. 30

2. A coin-controlled lock comprising a casing having a coin chute and a coin receiver, a bolt mounted to slide in said casing, said bolt being provided with a coin recess, a pivoted coin support below said recess, 40 said coin support having an extension beyond its pivotal point, a tumbler for moving said bolt, and a pivoted latch and stop for holding said bolt in projected position.

In testimony whereof I affix my signature 45 in presence of two witnesses.

HARRISON ELIGHUE LANE.
